LIFT PUMP

Ben Bohnenblust, Riley, Kans.

Application July 9, 1934, Serial No. 734,339

3 Claims. (Cl. 103—5)

This invention aims to provide a novel pump, in which the liquid is forced upwardly by the sliding movement of a cup-like barrel on a piston carried by an outlet conduit. The invention aims to provide novel means for supporting the barrel for sliding movement, to provide novel means for operating the barrel, to afford a novel connection between the barrel specified and a lower piston, to improve the cylinder construction, and to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawing:

Fig. 1 shows in longitudinal section, a device constructed in accordance with the invention, some parts being in elevation;

Fig. 2 is a transverse section on the line 2—2 of Fig. 1.

In carrying out the invention, there is provided a cylinder, which, as a whole, is designated by the numeral 1. The cylinder 1 comprises a lower member 2 and an upper member 3. The members 2 and 3 of the cylinder 1 are united by a coupling 4. A tubular housing 5 is disposed above the upper cylinder member 3. The housing 5 is surmounted by a cap plate 6. At its upper end, the housing 5 has an outstanding flange 7. Securing elements 8, such as bolts, connect the cap plate 6 to the flange 7 of the housing 5. At its lower end the housing 5 has an outstanding flange 9, and there is a similar flange on the upper end of the upper member 3 of the cylinder 1. A partition 10 is disposed between the flanges 9 and separates the interior of the upper member 3 of the cylinder 1 from the interior of the housing 5.

Securing devices 11, such as bolts, pass through the flanges 9 and the partition 10, the housing 5, the partition 10 and the upper member 3 of the cylinder thus being held together rigidly. Longitudinal guides 12, in the form of ribs, are located within the upper member 3 of the cylinder 1, and are connected to that member by securing devices 14, such as cap screws.

The numeral 15 designates, generally, an out-

let conduit. The outlet conduit 15 comprises a straight tube 16 threaded into the central part of the partition 10. The tube 16 extends upwardly above the partition 10, a little way, into the housing 5. The tube 16 extends downwardly a considerable distance into the upper member 3 of the cylinder 1. The outlet conduit 15 comprises an elbow 17 threaded on the upper end of the tube 16 and abutting against the partition 10. The elbow 17 extends laterally, out of the tubular housing 5. On the lower end of the tube 16 there is a fixed outstanding piston 18, of any suitable construction, it being unnecessary to describe the piston in detail, saving to state that it is adapted to make a water-tight contact with the 15 cup-shaped barrel 22, to be described hereinafter. In the lower end of the tube 16 there is a valve seat 19. A stop 20 is mounted in the tube 16, above the valve seat 19. A check valve 21 operates in the tube 16, between the stop 20 and the seat 19 and is adapted to open and close the seat. The check valve 21 is shown in the form of a ball, but it might be made otherwise.

The cup-shaped upper barrel 22, hereinbefore mentioned, preferably is of cylindrical form 25 throughout the major portion of its length. It is adapted to slide up and down upon the periphery of the piston 18 that is carried by the tube 16. The barrel 22 slides, also, on the inwardly projecting longitudinal guides or ribs 12 of the upper 30 member 3 of the cylinder 1, as Fig. 2 will show.

The operating members for the upper barrel 22 may be rods 23, located between certain of the ribs or guides 12, and secured at their lower ends to the upper portion of the barrel 22. The rods 23 35 pass slidably through the partition 10 and the cap plate 6. The upper ends of the rods 23 are secured detachably, as shown at 24, to a transverse yoke bar 25. An actuating rod 26 is secured at its lower end, as shown at 27, to the intermediate 40 portion of the yoke bar 25.

The cup-shaped upper barrel 22 has a tapered lower end 28 terminating in a central nipple 29. In the tapered lower end 28 of the barrel 22, above the nipple 29, there are inlet ports 30. The tapered lower end 28 of the barrel 22 is provided with an internal valve seat 31, located above the ports 30. A check valve 32 controls the passage of liquid through the opening of the valve seat 31. The check valve 32 closes downwardly. In 50 the drawing, it is shown hinged at 33 to the part 28 of the barrel 22. The check valve 32, however, might be mounted otherwise.

The upper end of a stem 34 is threaded into the nipple 29 on the part 28 of the barrel 22. The 55

lower end of the stem 34 is connected at 35 to a lower piston 36, operating in the lower member 2 of the cylinder 1. The lower piston 36 has upwardly opening check valves 37 of any desired construction.

The operation of the device is simple. On the downward movement of the rod 26, the yoke bar 25, the rods 23, the upper barrel 22, the stem 34 and the lower piston 36, the check valves 37 of the barrel 36 open, and the check valve 32 of the piston 22 opens. The liquid passes through the ports 30 of the barrel 22, into the barrel 22. On the upstroke, the valve 32 closes, and a quantity of liquid is trapped in the barrel 22, between the check valve 32 and the fixed piston 18 on the tube 16 of the outlet conduit 15. Since the barrel 22 moves upwardly, and since the piston 18 is fixed, the liquid in the barrel 22 is forced upwardly through the outlet conduit 15, the check valve 21 opening to permit the upward and outward passage of the liquid through the conduit 15.

The device simplifies packing problems. It is easily assembled and taken down. The barrel 22 is doubly guided, because it slides on the ribs 12, and because the rods 23 slide in the partition 10 and in the cap 6, as well. The tapered lower end 28 of the barrel 22 facilitates the downward movement of the barrel, and causes the water to enter rapidly through the ports 30. As to the final ejection of the water or other liquid through the conduit 15, that step in the operation does not depend upon a forcing action from the bottom of a well, but, rather, upon a combined lifting and forcing action taking place within the barrel 22.

Having thus described the invention, what is claimed is:

1. A pump comprising a cylinder, a top closure for the cylinder, means for securing the top closure to the cylinder, an outlet conduit fixed in the top closure and extended downwardly into the cylinder, the conduit being provided at its lower end with a fixed piston, a cup-shaped barrel receiving the piston and slidably thereon, the barrel

having a curved outer surface, a downwardly closing check valve in the lower portion of the barrel, more than two solid ribs on the interior of the cylinder and having, each, a single continuous surface engaged directly with the curved outer surface of the barrel to hold the barrel centered in the cylinder without interfering with the axial rotation of the barrel in the assembly of the pump, and an operating member slidably in the top closure and guided therein, to prevent the barrel from rotating with respect to the cylinder, after the top closure has been secured to the cylinder by the first specified means, the lower end of the operating member being connected to the upper portion of the barrel.

2. A pump comprising a cylinder, a tubular housing disposed above the cylinder, a partition located between the upper end of the cylinder and the lower end of the housing, a barrel mounted for reciprocation in the cylinder, a downwardly closing check valve in the lower portion of the barrel, means extended upwardly through the housing for imparting reciprocation to the barrel; an outlet conduit comprising an upper member fixedly mounted in a portion of the housing, and a lower member detachably connected to the partition and to the upper member of the conduit, a piston on the lower member, the barrel being slidably mounted on the piston, a downwardly closing check valve controlling the conduit, and means for securing the housing, the cylinder and the partition detachably together.

3. A pump comprising a cylinder, an outlet conduit fixed in the cylinder and provided at its lower end with a fixed piston, a cup-shaped barrel receiving the piston and slidably thereon, a downwardly closing check valve in the lower portion of the barrel, means for reciprocating the barrel, a lower piston slidably in the cylinder, below the barrel, and a connection between the lower piston and the barrel, and a downwardly closing check valve carried by the lower piston.
